ABSTRACT

A device for closing filled sacks and bags, such as refuse sacks, has a flat clamping plate with an opening to accommodate the gathered or twisted neck of the sack and accessible from the outside via resiliently spreadable gap in the plate. A carrying grip is formed by the web of a stirrup and two legs of the latter converge towards the sides of the grip in the direction of the plate.

DEVICE FOR CLOSING FILLED SACKS AND BAGS

BACKGROUND OF THE INVENTION

For closing filled sacks and bags, in particular refuse sacks, string is still used to a great extent, despite the fact that such ties are awkward when the sacks are very full and may also easily slip off during carrying if the sacks are smooth on the outside.

Because of this, other methods of closing filled sacks and bags have been sought and proposed; these methods involve clip-on clamping plates of springy plastics which close the neck of the sack after it has been gathered or twisted. These devices have an opening from the outside via a gap resiliently extensible to accept the neck of the sack.

Such closing devices are objectionable in objection that they are suitable only for small and light bags, and not for heavy sacks such as refuse sacks.

To ensure that the neck of the sack does not slip out of the opening in the case of heavy sacks, the clamping plate must have a powerful clamping action. Accordingly sufficiently strong pressure must be exerted to extend the gap and push the gathered or twisted neck of the sack therethrough.

SUMMARY OF THE INVENTION

In order to overcome all these disadvantages inherent to the clamping devices known heretofore, according to the present invention the clamping plate is provided with a stirrup-shaped member having two legs converging toward the clamping plate on either side of the gap, with the insides of the legs leading straight into the gap which in turn leads into the opening.

With a clamping device of the latter type, introducing the neck of the sack into the clamping plate is easier because the clamping plate can be fixed on the neck of the sack by pulling. Drawing this clamping device onto the sack requires far less effort than pushing-on or sliding-on the known grippless clamping plates. The design in accordance with the invention enables much more force to be applied when fitting the sack closure compared with the known clamping devices, and is therefore particularly suited for closing large and heavy sacks.

The structure according to the invention not only facilitates fitting the closure on the neck of the sack, but also makes it easy and convenient to lift up the sack and carry it away.

DESCRIPTION OF THE DRAWING

The accompanying drawing shows two embodiment of the invention and two modifications; in the drawing:

FIG. 1 is a front view of the device for use once only, in particular for refuse sacks;

FIG. 2 shows the device on a full sack in a sectional view taken on line II — II of FIG.1;

FIG. 3 is a diagrammatic representation of the device as applied to a full sack, on a reduced scale;

FIG. 4 is a first detail as modified to FIG.1;

FIG. 5 is a second detail as modified to FIG.1;

FIG. 6 is a front view of the device for repeated use, suitable for bags and light sacks; and

FIG. 7 shows a side view of the device illustrated in FIG.6 with the two halves twisted out of the plane of the plate.

SPECIFIC DESCRIPTION

Referring to FIGS.1 and 2, the device includes a clamping plate, designated 1, consisting of resilient material, with a central opening 3 whose inside edge is provided with serrations 2. Said opening serves to accommodate the neck 4' of a refuse sack 4 which is to be closed upon gathering or twisting of the neck. The clamping plate 1 has a gap 5 for introducing the neck 4' of the sack. This gap is partially obstructed by two points 6 acting as barbs which prevent the neck of the sack from moving out of the clamping plate once it is introduced. Encompassing the gap 5 and integral with plate 1 is a stirrup-shaped part 7 which has a web 7a serving as a carrying handle and two legs 7b converging towards the clamping plate to each side of gap 5 at the acute angle α so that their inside surfaces 7c lead straight into the gap 5. The clamping plate is provided with strengthening ribs 9 extending at right angles to its plane, which resist any twisting of the clamping plate from its plane.

On introducing the neck 4' of the sack into the opening 3, the twisted or gathered neck is first drawn through the inside space 8 encompassed by stirrup 7; the neck of the sack is drawn downwardly (FIG.2) by one hand, while the other hand pulls on stirrup 7. Owing to the tensile force applied to stirrup 7, the gap 5 is widened elastically so that the neck 4' can enter the opening 3, whereupon gap 5 and its barbs 6 spring back to their original positions so that the neck 4' of the sack cannot again pass out of the opening 3. The serrations 2 provide an additional safeguard against the neck 4' of the sack slipping out of the clamping plate when the sack 4 is lifted by the stirrup 7 and carried away.

With heavy sacks the safeguard against withdrawal of the neck 4' is enhanced further by the provision of a stud 11 on one side of the clamping plate 1, onto which the eye 12 of a closing strap 13 fixed to the other side of the plate is secured. As shown in FIG.2 the closing strap 13 holds the neck 4' of the sack in a sharply angled position on the clamping plate.

In the modification of FIG.4, the throat of the gap 5 has arranged therein only a single resilient barb 6'.

In the modification detailed in FIG.5 the gap 5 is also barred by only a single barb 6'', though of greater length. On introducing the neck 4' of the sack the barb 6'' is bent back elastically so as to widen the gap 5. After the neck 4' of the sack has been introduced the barb 6'' springs back to its starting position under its own elasticity.

The aforescribed device can conveniently be produced in one piece from tough, springy plastic such as hard PVC.

In the embodiment of FIGS.6 and 7, the clamping plate is designated at 1 and is provided with the opening 3', 5 leading into the opening. Barbs 6''' project into the opening at the bottom of a stirrup formed integral with the clamping plate 1, the web 7a serving as a handle, and the two legs of the stirrup 7b converging at an acute angle towards the clamping plate, the inside surfaces 7c of the legs running straight into said opening.

In contrast with the embodiment of FIGS.1 to 5, the system of FIGS. 6 and 7 neither the clamping plate 1 nor the stirrup 7 is strengthened with ribs. This makes it possible to bend or twist the clamping plate and stirrup out of the plane of the plate in two opposing direc-

tions as shown in FIG.7. The device according to FIGS.6 and 7 is intended for repeated use as a closure and carrying device for bags and lighter sacks, as for example those used for holding pulverulent or granular substances like chemicals, pharmaceuticals, detergents, etc. For such purposes the device according to FIGS.6 and 7 is a convenient closure and carrying grip. By twisting same as shown in FIG.7 it may easily be removed and used again without damaging the neck of the sack.

What I claim is:

1. A closure for a sack of flexible material having a neck, said closure comprising a generally flat plate formed with an opening adapted to receive said neck, and a slot leading to said opening at one side of said plate, a stirrup fixed to said plate and forming a grip at said side, said stirrup having a pair of linear legs converging in the direction of said slot and leading directly thereto for guiding said neck into said opening through

4
said slot, said legs including an acute angle between them; and a resilient barb extending from one of said legs into said opening and normally obstructing said slot while being deflectible upon insertion of said neck through said slot to enable said neck to pass and thereafter blocking withdrawal of said neck through said slot said plate having ribs extending at right angles to its plane to resist twisting of the plate.

5
10
2. The closure defined in claim 1, further comprising a strap affixed at one end to said plate, and mating formations at said plate and the other end of said strap for engagement upon slinging of said strap around said neck to hold the same at a sharp angle within said opening.

15
3. The closure defined in claim 1 wherein said plate and said stirrup are monolithically formed in a single piece from resilient material.
